UNITED STATES PATENT OFFICE.

KATHERINE LEWIS, OF CINCINNATI, OHIO, ADMINISTRATRIX OF WILLIAM W. LEWIS, DECEASED, ASSIGNOR TO EUGENE L. LEWIS, TRUSTEE, OF SAME PLACE.

STEAM-ENGINE.

SPECIFICATION forming part of Letters Patent No. 671,628, dated April 9, 1901.

Application filed January 5, 1901. Serial No. 42,221. (No model.)

To all whom it may concern:

Be it known that WILLIAM W. LEWIS, late a citizen of the United States residing at Hyde Park, in the county of Hamilton and State of Ohio, did invent certain new and useful Improvements in Steam-Engines, of which the following is a full, clear, and exact description, reference being had to the accompanying drawings, forming part of this specification.

This invention relates to steam-engines employing slide-valves, whether for marine, stationary, or locomotive engines, and especially to that class of engines, single or compound, which use the ordinary link which is in general use in all railroad service for the double purpose of varying the cut-off and reversing.

The object of the invention is to provide novel practical means which, without increased vibration of the rocker-arm, will give increased longitudinal play to the valve-rod to secure quick induction of live steam as well as a corresponding quick ejection of the steam after it has performed its work within the cylinder, so as to reduce the amount of compression to a point that will not obstruct the full development of power, and thereby obtain both economy in the use of steam and in the fuel necessary to produce it and also to produce accelerated speed of the engine.

To this end the invention consists in a rocker-arm having a bearing-surface co-operating with bearing projections on the valve-rod, which bearing-surfaces of the rocker-arm on opposite sides are so shaped as to impart both greater and quicker lineal movement to the valve on the opening sides of the ports for quick induction on one side and full and complete exhaust on the other side.

It also consists in certain preferred features of construction and adjustment whereby the results hereinafter stated are best accomplished.

The novelty of the invention will be hereinafter more fully set forth, and specifically pointed out in the claims.

In the accompanying drawings, Figure 1, Sheet 1, is a side elevation of an engine-valve mechanism, partly in section and partly broken away and illustrating the invention, the view being taken from a point between the wheels and looking outward. Fig. 2, Sheet 1, is a partial sectional central side elevation

of a cylinder, steam-chest, and slide-valve of the ordinary type and movement. Fig. 3, Sheet 2, is an enlarged side elevation, partly broken, of the improved rocker-arm, representing the same different positions and of one-third actual size for locomotive-work. Fig. 4, Sheet 2, is a sectional side elevation, partly broken, of a valve of the Allen type arranged in relation to the rocker-arm of Fig. 3, so that the relative positions of the two may be considered together. Fig. 5, Sheet 2, is a side elevation, diminished, of a modified form of the upper part of a rocker-arm embodying the invention and also showing its connection with the valve-rod. Fig. 6, Sheet 3, is a broken side elevation, partly in section, of the valve and rocker-arm with their respective parts, the valve being of the Allen type and the rocker-arm being shown in vertical position. Fig. 7, Sheet 3, is an enlarged plan view, one-third size, of the yoke inserted in the valve-rod and carrying the bearing-rollers which are confined in the slots of the upper part of the rocker-arm which passes through the opening in the yoke. Fig. 8, Sheet 3, is a transverse section on the dotted line $x-x$ of Fig. 7 looking to the right. Fig. 9, Sheet 3, is an enlarged side elevation of the outer bearing of the valve-rod illustrated in Fig. 6. Fig. 10, Sheet 3, is an end elevation of Fig. 9 looking to the left. Fig. 11, Sheet 3, is a diminished detail, in side elevation, of the parts making up the bearing of Fig. 9 disconnected from each other. Fig. 12, Sheet 4, is a diagrammatic view, in side elevation, of the present rocker-arm and that of a former rocker-arm in corresponding relations of movement, both in solid and dotted lines, to illustrate the increased travel of the valve-rod and valve of the present rocker-arm over that of the old rocker-arm when both are vibrated from the center to exactly the same distance.

The same letters of reference are used to indicate identical parts in all the figures.

Heretofore most rocker-arms of a link-motion gave a uniform motion to the valve, or at most accelerated the movement at mid-travel of the valve, which so far has proved of no practical benefit.

This invention provides a new and useful method for the purpose of an economical as

well as a more effective distribution of steam and may be practically applied to either stationary, marine, or locomotive engines, but more especially locomotives, whether they be 5 single or compound, whereby a larger development of both power and speed are obtained within shorter points of cut-off than is possible at the same points of cut-off applied to the ordinary valve-movement.

10 The principal reasons why the ordinary valve-movement is well known to be most defective, especially at short points of cut-off, are at least twofold—namely, an overamount of lead, especially at the center notch, for pre- 15 admission of steam before the piston reaches the end of the stroke, as well as a deficiency in the release of spent steam before the piston moves on its return stroke, which is no other than a loss of useful power and a de- 20velopment of negative power. The above-named defects are remedied by the improved valve-movement, no unequal setting of the forward eccentric from that of the backing eccentric being necessary, such as is resorted 25 to by some for the purpose of reducing the excessive lead in the working notch of the ordinary valve-movement. Nor does this improved movement require any abortive and wasteful appliance as that which is technically 30 known as "inside clearance" in order to give a more timely and somewhat-larger release, which is often resorted to in the use of the common movement, even in single engines, but more particularly so in those that are 35 compound. The above well-known defects of the ordinary valve-movement are entirely removed in the operation of my device, and in order to present reliable proof of the dif- 40ference between the ordinary valve-move- 45ment as compared with this improved move- 50ment it is said that the Chesapeake and Ohio Railroad Company by their assistant master mechanic of the western division took all the points of the valve-movement of two similar engines known as Nos. 46 and 47, the engine No. 46 being equipped with the ordinary valve-movement, while the engine No. 47 has this improved valve-movement, both of which are herewith submitted in tabular form for the 55 convenience of comparison. However, in advance of reference to the drawings it is said that the reason why this invention overcomes the defective points of the ordinary valve-movement is owing to the peculiar construction of the upper arm of the rocker, which 60 will be more particularly described later on, and at present it is merely stated that the central point of its movement when mechanically considered is really the starting-point 65 of its oscillation. It radically differs from the ordinary movement because it imparts a greater movement to both valve-rod and valve at the starting-point of its oscillation than it does when farther removed from the above-given point. This is shown in the table which will be hereinafter given and which shows that the engine No. 47, with the

reverse-lever hooked in the center notch, im- 70parted a movement at that point which instead of being cramped in the exhaust, as the ordinary movement must be, it moved the valve from its mid-travel point one-eighth of an inch beyond a full port-opening for the exhaust. Consequently the center notch of this device instead of being a nominal center 75 from which no useful work can be obtained, which is the case with the ordinary move- 80ment, produced a workable engine. This device shows not only a free and easy move- 85ment when operated in the center notch, but also develops power in proportion to the amount of steam admitted, and of course the same principle of development of increased power will be obtained within all the other points of cut-off, whereby all the useful power 90 is obtained within shorter points of cut-off than is possible to be obtained by the ordi- 95nary movement. Therefore inasmuch as this improved upper rocker-arm may be made to impart to the valve, even when the reverse- 100lever is hooked in the center notch, more than a full opening of port for the exhaust, it will be obvious that the difference of move- 105ment as compared with the ordinary move- 110ment requires greater length for the outside lap of the valve, so as to avoid the untimely preadmission of steam which would other- 115wise occur to such an extent before the pis- 120ton would terminate its stroke as to be of course inoperative, and yet while the outside of the valve will be about one-inch longer the exhaust-cavity is the same as that used in the ordinary valve, and the large movement of the valve accounts for the large difference of ex- 125haust.

105 As already stated in part, the improved distribution of steam is owing to the mechanical features of the bearings in the upper rocker-arm, with which the valve-rod is connected, and by referring to the drawings or comparing-table it will be found that at the central point of oscillation it will impart a lineal movement to the valve-rod one-third greater than the oscillating movement of the rocker. This is the result of finding the re- 115 quired proportion of convergence for the positive as well as divergence on the negative sides of the oscillations of the rocker-arm bearings, which in their connection with the valve-rod will be in constant and unvarying 120 bearings at all points of valve travel. How- 125ever, the convergence of the bearings in the rocker-arm must be designed so as not only to perform the functions which have been already referred to—namely, the induction 130 as well as the eduction of steam—but also the continuous rotary movement of the rollers in one direction. As applied to the induction it will be found that the relative convergence of the rocker-arm bearings, as shown by the drawings and comparing-table, does entirely remove the ordinary discrepancy between the full and mid-gear lead.

Now, referring to the drawings, in Fig. 1, A

represents the cylinder of a steam-engine; B, its piston; C, its piston-rod; D, the reciprocating slide-valve, and E the valve-rod. F is the ordinary link controlled by the arm G, with proper connections to the reversing-lever *a*, and operated in the usual manner by the oppositely-set eccentrics H on the crank-shaft. These parts are of the usual or any suitable construction and need not further be described. The link is connected in the usual manner to the usual lower rocker-arm I, whose shaft or journal has secured to it this novel upwardly-extending rocker-arm J. This rocker-arm J in its preferred form is best illustrated in Figs. 1, 3, and 6, where it is shown as a single steel casting with an upper projection containing through it a slot of peculiar formation. The manner of laying out this slot is best illustrated in Fig. 6, where K is a yoke interposed in and forming part of the valve-rod, whose adjacent and rear portions are rigidly secured to collars *b* on the extremities of the yoke. The yoke has through it from top to bottom a rectangular aperture *c*, in which are journaled on the axis of the valve-rod two rollers L and L', and these rollers are confined in the slot M of the rocker-arm before referred to, the upper part of which rocker-arm passes through the aperture *c* in the yoke. In the illustration given the valve D has a length on its bearing-face of nine and three-eighths inches, and the rollers L L' are exactly nine inches between centers and confined in the slot M of the rocker-arm, the width of which slot is just sufficient to accommodate the diameter of the rollers so as to give them play without binding. Now, returning to the manner of laying out the slot M on each upper projecting end of the rocker-arm, first assume a radial line *d* from the axis *e* of the rocker-arm when the rocker-arm is perpendicular, and on this radial line, which is likewise perpendicular, strike an arc *f* from the center *e*, the radius of which arc is eleven and seven-sixteenths inches. Then assume two other lines *g h* from the center *e* and forming radii of the arc and whose acute angle at the center *e* with the vertical line *d* is each thirteen and one-half degrees. The points of juncture *i j* of the radii *g h* with the arc *f* form the centers from which the bearing-curves *k l* of the slot M are struck on each side. The top ends of the slots are rounded, as shown, for neatness of appearance, and in order to lighten the rocker-arm their convergent lower ends may be united, forming one continuous slot M with two convergent bearing-surfaces, in which the rollers L L' are secured. For neatness of appearance the upper ends of the rocker-arms, on their upper and lower sides, follow the contour of the slot M. The effective upper end of the rocker-arm will be a line through the axis of the valve-rod, and the distance of this axial line from the center *e* of the rocker-arm is, in the illustration given, nine and three-quarters inches.

For the purposes of ordinary locomotive-

work it has been found from actual experience that the above proportions give the results at which this invention is aimed and are perfectly safe to follow. In other cases, where the valve is shorter or longer, the same proportions may be employed both as to the distance between the centers of the rollers and the length of the arc from which the centers are found in laying out the curves to form the operating-bearings in the slot of the rocker-arm.

In Fig. 5 is shown a modified form of rocker-arm embodying this invention, but made up of separate pieces for purposes of adjustment and taking up wear; but this arm also follows the rules described with reference to the arm in Fig. 6, and here it will be observed that the lower or connecting part of the slot M is dispensed with and only the bearing portions on the opposite sides which engage the rollers are retained.

In Fig. 1 is shown a type of valve somewhat similar to the ordinary valve, but of a length equal to that of the valve shown in Fig. 6, covering the inlet-ports *n o* and the exhaust-port *p*, and the rocker-arm is shown as thrown slightly in advance, so as to fully uncover the port *n* to the exhaust and slightly open the inlet-port *o*, while in Fig. 2 the ordinary type of valve, which is about one inch shorter than that of Fig. 1, is represented as being coupled to the ordinary form of rocker-arm, which occupies the same position as the rocker-arm of Fig. 1. It will be observed from these two figures that while the pistons are both in the same position the positions of the valves are not the same, the valve in Fig. 1 showing a trifle more than a full exhaust-opening. It shows just enough steam-opening to form an effective cushion to prevent the sudden reversing of the motion of the piston from causing a jar to the engine, while the valve in Fig. 2 instead of showing a full exhaust-port shows but a trifle more than half a full exhaust-port, and the steam-port instead of forming an effective cushion for the piston to prevent the jar or jolt is open to such an extent that it would produce a negative power in the cylinder which would very materially diminish the power and speed of the engine.

Now, referring to Fig. 4, where a valve of the Allen type is shown in connection with this improved rocker-arm, its operation with that of the ordinary rocker-arm is compared, as follows: In said figure the rocker-arm is advanced from its perpendicular position the distance between the points *a' b'* on the dotted line indicated which is coincident with the axis of the valve-rod, and this movement of the rocker has carried the rollers a greater distance, approximately one-third, as indicated by the distance between the centers of the rollers shown in dotted lines and the centers of those shown in solid lines. This movement of the rocker-arm will have carried the valve shown in Fig. 4 from a position indicated by the dotted line *c'* to the position shown by the solid lines, where it will be no-

ticed that more than a full exhaust-port is obtained and that a very sufficient steam-opening is obtained both in the crossover-port and in the direct port, while if the same 5 valve were applied to the ordinary movement it would fail of opening by the distance shown from the position of the valve shown in the dotted line d^2 to the edge e^2 of the port o . However, if the ordinary length were applied 10 to the present improved rocker-arm the steam-port would be opened to such an extent that it would be impossible to run the engine. The arrow f^2 indicates the amount of opening that the ordinary valve would have as applied to 15 the present improved rocker-arm.

In Fig. 12, which is a diagrammatic view, is compared the gain of valve-movement of the present rocker-arm with the same extent of rocker-arm movement of a former patent taken out by William W. Lewis, the present inventor, jointly with Jéptha Garrard, No. 510,128, dated December 5, 1893, the upper figure representing the present rocker-arm and the lower figure representing the Garrard and Lewis construction. The dotted lines show both rocker-arms vertical and the solid lines their forward throw to exactly the same extent, as indicated by the arrows g' . With this equal throw of both the rocker-arms it will

be seen that with this present construction 30 there is a considerable gain, as indicated by the dotted line h' , connecting the two vertical lines from the centers of the upper rollers over the dotted line i' connecting the vertical dotted line extending from the centers of the 35 two lower rollers in their changed positions, and that by the use of this present form of rocker-arm, with the acting parts of its slots converging toward the center of the rocker-arm and the upper parts of said slots diverging therefrom, it is possible to obtain a quicker 40 and larger throw of the valve from mid-travel in either direction, and thus obtain a quicker and complete exhaust before the admission of steam to the opposite end of the cylinder, 45 and thereby at the central notch or mid-gear of the reversing-lever an efficiency of the engine is obtained which could not heretofore be obtained at mid-gear by any previous construction, and which efficiency is increased 50 by the movement of the lever a to any notch from the center. This difference and the results obtained are clearly illustrated by the tables which follow, the first table representing the operation of engine No. 46 with the 55 old form of rocker-arm and the second table representing engine No. 47 equipped with the present invention.

Engine No. 46.

Engine No. 47.

It will be seen from the foregoing tables that not only is a greater power obtained at the center notch (represented by 1 in the left column of each table) than is obtained by the ordinary rocker-arm, but for each notch in advance of the center this power is greatly augmented over that of the ordinary rocker-arm, for from mid-travel each way the valve is given a quick movement and a longer movement than the ordinary valve, so that a quick and complete exhaust is obtained on the one side before the induction sufficient for cushioning occurs on the opposite side.

Now, referring to Figs. 7, 8, 9, 10, and 11, the details of construction of the roller-bearings and the support for the rear end of the valve-rod will be described. As seen in Figs. 7 and 8, there is a plug M' passed through taper apertures in the side walls of the yoke K for each of the rollers L L', which fits snugly between the side walls of the yoke, and the rollers bear on them. The outer ends of these plugs are threaded to receive fastening-nuts N, and into the larger end of each plug is a central bore O, into which is fitted the end of an oil-cup P, which discharges its lubricant through a channel a' from the bore O into the bearings of the rollers. The bearing for the rear end of the valve-rod is composed of a central sleeve Q, on the ends of which are first fitted rings R, having lower threaded stems which pass through apertures in a flange S of a bracket T, suitably secured to the framework of the engine. These stems b' are held in place by nuts c', and outer rings U are finally screwed on the threaded ends of the sleeve Q. This construction forms a very secure and at the same time adjustable bearing for the rear end of the valve-rod which passes through it. Oil-cups d' and e' are provided for the valve-rod bearing and the upper ends of the slots in the rocker-arm, respectively, for purposes of lubrication, as will be readily understood.

Having thus fully described the invention, what is claimed is—

1. The combination of a valve and its rod having actuating-bearings, of a rocker-arm having curved bearing-surfaces on opposite sides constantly engaging the bearings, said curved bearing-surfaces converging at their inner ends toward the axis of the rocker-arm and diverging therefrom at their outer ends, whereby after mid-travel in either direction a quicker and increased movement is imparted to the valve, substantially as described.

2. In the valve-gear of an engine, the combination of a slide-valve for the cylinder, a valve-rod connected to the slide-valve and having bearings carried thereby, a rocker-arm having on opposite sides thereof curved slots engaging said bearings, said slots converging at their inner ends toward the axis of the rocker-arm and diverging therefrom at their outer ends, a lower extension of said rocker-arm, link gearing actuated by a lever and eccentrics on the piston-driven shaft con-

nected to said link gearing, whereby the throw of the valve may be varied at will, substantially as described.

3. The combination of a valve and its rod having actuating bearing-rollers, of a rocker-arm having curved bearing-surfaces on opposite sides constantly engaging the bearing-rollers, said curved bearing-surfaces converging at their inner ends toward the axis of the rocker-arm and diverging therefrom at their outer ends, whereby after mid-travel in either direction a quicker and increased movement is imparted to the valve, substantially as described.

4. In the valve-gear of an engine, the combination of a slide-valve for the cylinder, a valve-rod connected to the slide-valve and having roller-bearings carried thereby, a rocker-arm having on opposite sides thereof curved slots engaging said rollers, said slots converging at their inner ends toward the axis of the rocker-arm and diverging therefrom at their outer ends, a lower extension of said rocker-arm, link gearing actuated by a lever and eccentrics on the piston-driven shaft connected to said link gearing, whereby the throw of the valve may be varied at will, substantially as described.

5. In the valve-gear of an engine, the combination of a slide-valve for the cylinder, a valve-rod connected to the slide-valve, a yoke in said valve-rod having roller-bearings carried therein, a rocker-arm, the upper end of which extends through said yoke having on opposite sides thereof curved slots engaging said rollers, said slots converging at their inner ends toward the axis of the rocker-arm and diverging therefrom at their outer ends, a lower extension of said rocker-arm, link gearing actuated by a lever and eccentrics on the piston-driven shaft connected to said link gearing, whereby the throw of the valve may be varied at will, substantially as described.

6. In valve-gear of the character described, the combination of the yoke K with vertical apertures c therethrough, the rollers L L' journaled in said yoke, the rocker-arm J having its slotted upper end extending through the yoke with the rollers L L' confined and bearing in the slots of the rocker-arm, substantially as described.

7. In valve-gear of the character described, the combination of the yoke K with vertical apertures c therethrough, the rollers L L' journaled on bearings through said yoke having tapering seats therefor and held by nuts N, the rocker-arm J having its slotted upper end extending through the yoke with the rollers L L' confined and bearing in the slots of the rocker-arm, substantially as described.
